UNITED STATES PATENT OFFICE.

WILLIE O. BESAW AND ALLEN E. McCLANAHAN, OF REEDLEY, CALIFORNIA.

HAND-STAMP.

1,282,173.

Specification of Letters Patent. Patented Oct. 22, 1918.

Application filed March 20, 1917. Serial No. 156,071.

To all whom it may concern:

Be it known that we, WILLIE O. BESAW and ALLEN E. McCLANAHAN, citizens of the United States, residing at Reedley, in the 5 county of Fresno, State of California, have invented certain new and useful Improvements in Hand-Stamps; and we do hereby declare the following to be a full, clear, and exact description of the invention, such as 10 will enable others skilled in the art to which it appertains to make and use the same.

This invention relates to new and useful improvements in hand stamps and aims to provide a device of this character adapted 15 for use in stamping mail, with the figures designating the amount of postage required to transmit said mail, thus obviating the use of postage stamps as at present practised.

20 A further object of the invention is to provide a hand stamp which can be set to stamp the desired amount of postage which may vary in specific cases.

A further object of the invention is to 25 provide novel means for setting the stamp to attain the above object.

A further object of the invention is to provide means whereby the stamp may be operated a predetermined number of times 30 and when said predetermined number of operations has been completed, the machine is locked against further operation.

A further object of the invention is to provide in combination with a machine of this 35 character a series of elements for dating, thus making the record on the mail of the date stamped.

Referring to the drawings:

Figure 1 is a perspective view of the complete device,

Fig. 2 is a sectional view of the device on the line 2—2 of Fig. 1,

Fig. 3 is a vertical sectional view on the line 3—3 of Fig. 2,

Fig. 4 is a vertical sectional view on the line 4—4 of Fig. 2,

Fig. 5 is a detail view,

Fig. 6 is a detail view,

Fig. 7 is a detail view of a portion of the machine, and

Fig. 8 is a detail view of the value strip used in connection with the machine.

Referring more particularly to the drawings the reference character 1 designates a 55 base which is of substantially box-shape and has its upper wall provided with spaced

openings 2 between which is mounted a vertically extending standard 3.

Slidably mounted upon the vertical standard 3 and the outer wall of a hollow handle 4, and arranged between the upper end of the vertical standard 3 and the outer wall of a hollow handle 4 is a coil spring 5. Secured to the hollow handle 4 and depending therefrom is an inverted U-shaped member 6, the legs of which 65 extend through the spaced opening 2 and lie within the confines of the inverted box-shape 1.

The lower end of the legs of the inverted U-shaped member 1 are provided with perforations 7, and mounted in said perforations 7 is a longitudinally extending shaft 8, one end of which is squared as at 9.

Mounted for rotation upon said shaft 8 are rolls 10 and 11, the roll 11, being between the depending legs of the inverted U-shaped member, while the roll 10 is between the side wall of the box and the adjacent leg of the member 6, the roll 10 being provided with abbreviations designating the 75 months of the year and the roll 11 being provided with numerals to designate the days of the month, and mounted within the confines of the inverted U-shaped member 6 is a third roller 12 which carries characters 80 designating different years. Each of these three rollers are manually operated to set them to the desired month, day and year.

Mounted adjacent the roller 12 and secured to the shaft 8 in any suitable manner 90 so that it will rotate therewith is a roller 13 which roller is provided with designating characters representing different values of postage, and rigidly secured to said roller is a ratchet member 14, the purpose of which will be hereinafter described.

Loosely mounted on the shaft 8 adjacent the roller 13 is a roller 15, the periphery of which is provided with a plurality of 100 equally distant spaced teeth 16, and carried by said roller on opposite sides thereof are ratchet members 17 and 18. Carried by the roller 13 is a pawl 19 which is adapted to engage the ratchet member 17 to operate the toothed roller 15, and pivoted to the depending member of the inverted U-shaped member 6 is a pawl 20 which is adapted for engagement with the ratchet member 18 to prevent the turning of the toothed roller in one direction. Having one of its ends secured to the shaft 8 and its other end secured to one of the rearwardly extending 105 110

members 21 of the inverted U-shaped member 6 is a coil spring 22 against the action of which the shaft 8 is rotated.

Rigidly secured to the outer face of the 5 side member of the inverted U-shaped member 1 is a spring 23, and swiveled on the lower end of said spring is an operating nut 24 having a squared opening 25, said opening being adapted for engagement with the 10 squared end of the shaft 8, to provide means for operating the same.

Extending rearwardly from the depending member 6 near the lower end thereof are brackets 21 and 26 which are connected by 15 means of a transverse brace or the like 27, and overlying the bracket 26 is a second bracket 28 which is secured near the upper end of one of the side members of the inverted U-shaped member 6. Secured to the 20 bracket member 28 and extending transversely of the machine is a member 29 on which is secured a spool 30 by means of the set screw 31, and wound around said spool is a strip of paper which is provided with 25 a plurality of equally distant spaced perforations 32, the said perforations 32 being adapted to engage the pins or teeth 16 of the toothed roller 15.

Secured in the depending members of the 30 inverted U-shaped member 6 and overlying the rollers 12, 13 and 15 is a transversely extending shaft 33, and rigidly carried thereby is a pawl 34, the forward end of which is curved as at 35 to provide a depending member 36 adapted to engage the ratchet member 14. This pawl is extended rearwardly and is connected to the bracket 28 by means of a coil spring 37 which tends to lift the rear end of said pawl and maintain 40 the forward end thereof in engagement with the ratchet member 14.

Loosely mounted on this transverse shaft 33 is a rearwardly extending pawl 38 which is adapted to contact with the perforated 45 strip 31 for a purpose which will be herein-after described.

Secured to the box-shape member 1 is a member 39 having a depending portion 40 which is adapted to engage the rear end of 50 the pawl 34 to disengage its forward end from the ratchet member 14 during the operation of the machine.

The box-shape member 1 is provided with a suitable opening 46 closed by a door 47 and 55 secured in closed position by means of a seal 48.

Having thus described the invention, the operation thereof is as follows:—

It is intended that the stamp be the property of the party using the same, and when 60 it is desired to use the stamp, said party takes the same to the postoffice where he purchases a spool of perforated paper 31 which when the seal has been broken and 65 the casing opened is inserted on the spool

supporting member 29, the free end of said perforated paper being fed over the toothed roll 15 and having its first perforation engaged with one of the teeth 16 thereof. When the machine is thus set the casing is 70 closed and a seal applied to prevent tampering with the interior mechanism thereof.

If the mail to be stamped requires for example four cents in postage the operating nut is engaged with the square extremity 9 75 of the shaft 8 and said shaft is turned to bring the numeral 4¢, to the printing position, in which position it is maintained by means of the forward extremity of the pawl 34 engaging the ratchet member 14. This 80 operation also turns the toothed roller and discharges the paper strip 31 from the machine correspondingly, each of the openings 32 in said paper strip 41 representing the value of one penny. This toothed roller 15 85 is caused to rotate by reason of the pawl engaging the ratchet member 17 thereof, and this roller is prevented from turning in a rearwardly direction by means of a pawl 20 engaging the ratchet member 18.

When the rollers 1, 11 and 12 have been set to designate the month, day and year, the handle 4 is grasped and the inverted U-shaped member 6 is depressed to contact the several rolls with the printing surface.

Upon depression of the inverted U-shaped member 6, the rear end of the pawl 34 engages the depending spring member 40 and owing to the resiliency thereof passes the same freely. When the handle 4 is depressed, however, the spring 5 returns the inverted U-shaped member 6 to normal position and the rear end of the pawl 34 engages the spring member 40 thus releasing the roller 13 and permitting the same to return to normal position under the influence of the coil spring 22.

From the foregoing it will be seen that the device is capable of use to stamp mail matter with any desired amount of postage.

Near the inner end of the strip 31 is provided an elongated slot 49 and when the strip has been exhausted the pawl 38 projects through said slot and engages one of the teeth 16 of the toothed roller 15 thus locking the machine against further operation until the same has been taken to the post-office and reloaded with a spool of perforated paper.

These spools of perforated paper are of 120 different denominations and can be purchased as desired by the holder of the machine and for example instead of buying 100 stamps, a roll of paper having 100 perforations would be purchased and placed in the 125 machine by the postmaster thus doing away with stamps as is the present practice.

The box-shape member 1 may be provided on its lower extremities with a rigidly attached printing element 50 which is pro-

vided with designating characters 51 to indicate the postoffice at which the machine was loaded and other designating characters as desired.

5 Inking mechanism is provided which comprises an inking pad 52 which is adapted to lie in engagement with the stamping rollers when in their elevated position as shown in Fig. 3. The roller 13 has arranged thereon a suitable stop 53 which is adapted to be engaged by the pawl 34 for limiting the return of said roller at zero position.

What is claimed is:—

1. A device of the character described comprising a base, an operating member carried by the base, a printing element carried by the operating member, means carried by the base for setting the printing element, means for retaining the printing element in set position, said retaining means adapted to be disengaged to release the printing element to permit the same to return to normal position upon operation of the machine.

2. In a device of the character described, a base, an operating element carried by the base, a printing member carried by the operating member, means for setting the printing element, means for retaining the element in its set position, means for feeding a strip of paper through the device, said means being operated by the setting operation of the printing element, and means limiting the paper feeding means to movement in one direction only.

3. A device of the character described comprising a base, an operating element carried by the base, printing elements carried by the operating element, means for setting one of said printing elements, means for retaining the printing element in its set position, means for returning the printing element in normal position upon operation of the operating element, means for feeding a strip of paper through the machine, said paper feeding means depending upon the setting operation of the printing element for its operation, and means for preventing movement of the paper feeding means upon resetting of the printing element.

4. A device of the character described comprising a base, operating elements supported by the base, printing elements carried by the operating element, means for setting one of the printing elements, paper feeding means operated by the setting of the printing element, means for retaining the printing element in set position, means operating to permit the printing element to return to

normal position, and means operating to prevent movement of the paper feeding means during the return of the printing element to normal position.

5. A device of the character described comprising a base, an operating element carried by the base, printing elements carried by the operating elements, means for adjusting one of the printing elements, means for retaining said printing elements in adjusted position, and means for returning said adjusted printing elements to normal position upon operation of the machine.

6. A device of the character described comprising a base, an operating element carried by the base, a shaft carried by said operating element, a plurality of printing elements carried by the shaft, one of said printing elements being rigidly secured thereto, means for rotating the shaft to adjust said rigidly secured printing element, means for retaining the printing element in adjusted position, and means for permitting of said printing element returning to normal position upon operation of the machine.

7. A device of the character described comprising a base, an operating element movable with respect thereto, a shaft carried by said operating element, printing elements carried by the shaft, means engageable with the shaft for setting one of the printing elements carried thereby, means for maintaining said printing element in its set position, and means for releasing said printing element to permit of its returning to normal position upon operation of the operating element.

8. A device of the character described comprising a base, an operating element movable with respect thereto, printing elements carried by the operating element, means for adjusting one of the printing elements, means for retaining said adjustable printing element in its adjusted position, and means carried by the base for engagement with said printing element retaining means to disengage the latter and permit of the printing element returning to normal position upon the operation of the operating element.

In testimony whereof we affix our signatures in the presence of two witnesses.
